UNITED STATES PATENT OFFICE

BERTHA V. LAING, OF DEARBORN, MICHIGAN, ASSIGNOR TO LAING AND COMPANY, A CORPORATION OF MICHIGAN

SEWING KIT

Application filed February 26, 1930. Serial No. 431,514.

This invention relates to sewing kits or cabinets, and aims to provide a novel form of cabinet wherein spools of cotton may be supported in position so that the cotton may be readily removed from the spools without danger of the cotton tangling.

An important object of the invention is to provide a device of this character embodying an upper compartment to retain the spools 10 of cotton, and a lower compartment to contain scissors, pin cushion, needles, thimble and other articles used in sewing, so that a person may have easy access thereto.

A further object of the invention is to provide means adjacent to the spools, so that the cotton thread may be readily cut without the necessity of unwinding great lengths of the cotton, which often happens when the cotton or thread is broken.

With the foregoing and other objects in view, which will appear as the description proceeds, the invention resides in the combination and arrangement of parts and in the details of construction hereinafter described 25 and claimed, it being understood that changes in the precise embodiment of the invention herein disclosed, may be made within the scope of what is claimed, without departing from the spirit of the invention.

Referring to the drawing:

Figure 1 is a perspective view of a sewing kit, the cover of one of the compartments thereof being shown in its open position.

Figure 2 is a sectional view taken on line 35 2—2 of Figure 1.

Figure 3 is a sectional view through the body portion of the device, the covers thereof being in their closed positions.

Referring to the drawing in detail, the 40 device comprises a body portion indicated generally by the reference character 5, the same being provided with a sloping front wall 6 that is cut away defining an opening which is normally closed by the hinged closure 7.

The rear wall of the body portion is bent

downwardly at 8 and forwardly where it contracts with the front wall of the body portion, the free extremity of the curved portion of the rear wall, extending downwardly at 9, where it is disposed beyond the upper edge 50 of the opening in the front wall of the body portion, defining a rest or support for the closure 7.

As clearly shown by Figure 1 of the drawing, the upper edge of the front wall is 55 formed with pairs of spaced parallel slots 11 defining blades 12 which are slightly twisted to present sharp cutting edges. Openings 13 are also formed in the front wall of the body portion, through which 60 openings the threads of the spools mounted in the spool compartment extend, so that the threads may be pulled and the desired length of thread removed from the spools, without the necessity of removing the spools 65 from the spool compartment.

The spool compartment is normally closed by means of the curved closure 14, which is hingedly connected to the body portion at 15. Thus it will be seen that by raising the 70 closure 14, access to the spools may be had, so that the spools may be removed and replaced with facility.

A removable needle threader is indicated by the reference character 16 and is removably 75 supported within the closure 14.

This cabinet, while it holds spools in such positions with respect to each other that the threads may be readily removed therefrom, also provides a compartment to receive and 80 contain such other articles employed in sewing, as pin cushion, needles, scissors or the like.

I claim:

A sewing cabinet comprising a body portion, said body portion having its front wall cut away providing an opening, a curved partitioning member forming a continuation of the rear wall of the cabinet and extending downwardly and upwardly, the front 85 90

edge of the partitioning member extending downwardly and being secured to the front wall of the cabinet, a portion of the partitioning member extending beyond the upper edge of the opening, providing a rest, a closure for closing the opening of the cabinet, and one edge of the closure engaging the rest to support the closure.

In testimony that I claim the foregoing as my own, I have hereto affixed my signature.

BERTHA V. LAING.
